[57] **CLAIM**

The ornamental design for a working and serving board with a removable strainer, substantially as shown and described.

DESCRIPTION

FIG. 1 is a top plan view of a working and serving board with removable strainer showing my design; FIG. 2 is a side elevational view thereof.

FIG. 3 is a top plan view of a serving board including an aperture adapted to receive a removable strainer and a movable handle,

FIG. 4 is an end view thereof showing the end adjacent to the aperture,

FIG. 5 is an end view thereof showing the end adjacent to the movable handle,

FIG. 6 is a side view thereof, the opposite side being the reverse thereof,

FIG. 7 is a bottom plan view thereof showing the sliding handle in a closed position,

FIG. 8 is a top plan view of a removable strainer adapted to nest in the aperture of the serving board of FIGS. 3 and 7,

FIG. 9 is a bottom plan view of the strainer of FIG. 6,

FIG. 10 is a side elevation view of the strainer of FIG.

6, the opposite side, not shown, being identical,

FIG. 11 is a front elevation view of the strainer of FIG.

6, the opposite side not shown, being identical,

FIG. 12 is a top perspective view of the serving board of FIGS. 3 through 7 inclusive;

FIG. 13 is a cross-sectional view taken in the direction of the arrows on line 13—13 of FIG. 12; and

FIG. 14 is a cross-sectional view taken in the direction of the arrows on line 14—14 of FIG. 12.
